SPRAY NOZZLE

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application July 18, 1947, Serial No. 761,801

2 Claims. (Cl. 299—121)

1

This invention relates to nozzles for producing conical liquid sprays.

It is the general object of the invention to provide a nozzle which will produce a conical spray which is widely and uniformly diffused, instead of being closely concentrated in a limited cross section.

To the accomplishment of this general object, a spray nozzle is provided which in the preferred form provides concentric annular hollow streams of liquid which are rotated in opposite directions as they emerge from the nozzle.

The invention further relates to arrangements and combinations of parts which will be herein-after described and more particularly pointed out in the appended claims.

Preferred forms of the invention are shown in the drawings, in which

Fig. 1 is a sectional side elevation of a preferred nozzle construction;

Fig. 2 is a perspective view of an annular partition and associated vanes shown in Fig. 1; and

Figs. 3 to 8 inclusive are sectional side elevations showing modified constructions.

Referring to Fig. 1, a spray nozzle is shown comprising an outer casing 10 having its end portion 10a contracted to provide a nozzle opening 11. A tube 12 is mounted within the casing 10 and in spaced relation thereto, and the open end 14 of the tube preferably terminates slightly inward of the nozzle opening 11.

An annular partition 16 is mounted between the casing 10 and the tube 12 and is curved to approximately correspond to the curvature of the casing part 10a. Outer vanes 18 are mounted between the casing 10 and the partition 16, and inner vanes 19 are mounted between the partition 16 and the tube 12. The vanes 18 and 19 are welded or brazed or otherwise secured to the parts 10, 12 and 16 and serve to hold these parts in fixed spaced relation.

The vanes 18 and 19 are approximately axially disposed at their entering or left-hand portions as viewed in Fig. 1, but are reversely curved at their delivery portions. Inner and outer hollow liquid streams will thus be delivered through the nozzle opening 11, these inner and outer streams will be rapidly rotated but in opposite directions. This results in effective intermingling of the two streams into a single conical spray of very uniform density and large cross section.

In the construction shown in Fig. 3, the partition 20 is similarly provided with outer vanes 21 and inner vanes 22, but the outer vanes are of substantially greater width than the inner vanes,

2

so that the partition 20 is relatively nearer to the tube 23. A larger proportion of the liquid is thus delivered through the outer vanes, and the resultant spray will be correspondingly more dense in its outer portion.

In Fig. 4, a plurality of vanes 30 are provided outside of a partition 31 and the inner set of vanes is omitted. The inner tube 33 may be positioned by radial supports 34. This construction provides a non-rotating hollow stream within in a rotating hollow stream, so that the resultant spray is more dense in its inner portion.

In Fig. 5, the outer set of vanes 40 is connected to an outer partition member or sleeve 41, and the inner set of vanes 42 is connected to an inner partition or sleeve 43. The partitions 41 and 43 are spaced apart to provide an annular cylindrical passage 46 through which a non-rotating stream of liquid may be projected between oppositely rotating outer and inner hollow streams. The inner tube 47 may be positioned by radial supports 48. This type of nozzle is found to produce a spray of very uniform density.

In the construction shown in Fig. 6, outer vanes 50 are mounted within the casing 51 and inner vanes 52 are mounted on the tube 53, while the annular partition member is entirely omitted. The inner tube 53 is positioned by radial supports 56. This construction gives good results and is somewhat simpler than the construction shown in Fig. 1.

In Fig. 7 the construction is still further simplified by providing an annular set of relatively short vanes 60 mounted within the outer casing 61 and substantially spaced from the inner tube 62, which inner tube has radial supports 63.

In the construction shown in Fig. 8, three concentric partitions 70, 71 and 72 are mounted between the casing 74 and the inner tube 75. Four sets of vanes 76, 77, 78 and 79 are provided in the annular passages between the outer casing, the inner tube and the three concentric partitions, as clearly shown in Fig. 8. Furthermore, the delivery ends of the outer and inner partitions 70 and 72 are extended beyond the delivery opening of the nozzle and are outwardly and inwardly flanged as shown, so that portions of the liquid stream are directed outwardly through the opening 80 and inwardly through the opening 81. Preferably, adjacent sets of the vanes 76 to 79 are oppositely curved.

By varying the spacing of the several partitions, the density of the resultant spray may be effectively controlled.

Having described a preferred form of the in-

vention and several modifications thereof, it will be understood that the invention is not to be limited to the details herein disclosed, otherwise than as set forth in the claims, but what is claimed is:

1. A spray nozzle comprising an open inner tube and a concentric encircling outer tube defining an annular liquid passage having an outlet end part, an annular partition mounted adjacent said outlet end part of said passage and extending lengthwise of said end part only and dividing said outlet end part of said annular passage into separated inner and outer passage portions, and a plurality of angularly disposed vanes mounted in said inner passage portion and in said outer passage portion of said annular passage respectively and inside and outside of said annular partition, and the vanes in said inner and outer passage portions being oppositely inclined.

2. A spray nozzle comprising an open inner tube and a concentric encircling outer tube defining an annular liquid passage having an outlet end part, an annular partition mounted adjacent said outlet end part of said passage and extending lengthwise of said end part only and dividing said outlet end part of said annular passage into separated inner and outer passage

portions, and a plurality of angularly disposed vanes mounted in said inner passage portion and in said outer passage portion of said annular passage respectively and inside and outside of said annular partition, and the vanes in said inner and outer passage portions being oppositely inclined, and said annular partition being positioned substantially nearer said inner tube than said outer tube and thereby relatively increasing the capacity of said outer passage portion.

ESTHER C. GODDARD,
*Executrix of the Last Will and Testament of
Robert H. Goddard, Deceased.*
